UNITED STATES PATENT OFFICE.

WILLIAM D. SCHAEFER, OF CHICAGO, ILLINOIS.

HAIR CURLER.

Application filed July 5, 1923. Serial No. 649,497.

To all whom it may concern:

Be it known that I, WILLIAM D. SCHAEFER, a citizen of the United States, residing in Chicago, in the county of Cook, 5 and State of Illinois, have invented certain new and useful Improvements in Hair Curlers, of which the following is a specification.

This invention relates to devices for curling the hair and has for its primary object to provide a compact, inexpensive and efficient device of this character.

Further objects of my invention are to provide a device which may be worn with comfort while sleeping and which will not accidentally open or permit the hair to become released therefrom, to eliminate the necessity for heating the iron, to facilitate the winding of the hair upon the iron, and 20 in general to provide a novel and improved device of this type.

The many other advantages of my invention will be better understood by reference to the following specification when 25 considered in connection with the accompanying drawing illustrating a selected embodiment thereof, in which:—

Fig. 1 is an enlarged side elevation of a curling iron embodying my invention, the 30 parts being in closed or folded position.

Fig. 2 is the same as Fig. 1, the parts being in extended position.

Fig. 3 is the same as Fig. 2 with the iron 35 opened to receive a lock of hair.

Fig. 4 is a transverse section on the line 4-4 of Fig. 1, and

Fig. 5 is an end elevation in closed position.

Referring to the drawing, the curling 40 iron comprises a substantially U-shaped handle of spring metal and co-operating curling members 11 and 12 pivotally connected to the opposite ends of the handle by pins or rivets 13 and 14 respectively.

The inner portions 15 and 16 of the members 11 and 12 respectively are bent into hook form. In the present embodiment the outer portion of the member 11 is substantially cylindrical in cross section while 45 the hook-shaped inner portion thereof is flattened. The outer portion of the member 12 is trough-shaped while its inner portion is substantially square. This square portion of the member 12 is provided with an 50 elongated slot at 17 through which the flat-

tened portion of the member 11 extends and in which this member operates. These members are held tightly together by the spring action of the handle.

The member 11 is preferably slightly 60 longer than the member 12 and its end is preferably provided with a notch 18 to engage a boss 19 in the bend of the handle when the curling iron is in closed position. The trough-shaped portion of the member 65 12 preferably fits about the periphery of the corresponding portion of the member 11.

To extend the iron the oppositely disposed side portions of the handle are pressed inwardly, flattening the loop and causing the 70 boss 19 to be withdrawn from the notch 18. The members 11 and 12 are then rotated on their respective pivots to the position of Fig. 2. To expand the iron to receive a lock of hair the sides of the handle are again slightly compressed, causing the members 11 and 12 to be spread in the manner indicated in Fig. 3. The end of the lock of hair is next inserted between these members and the pressure on the handle released. The iron resumes the position of Fig. 2 with the hair firmly held between the members. The iron is then rotated to cause the hair to be wound thereon in the usual manner. When the winding has 80 progressed sufficiently, the iron is folded to closed position with the boss engaging the notch in the member 11. The hair cannot become unwound when the iron is in this position and the firm grip of the members 11 and 12 prevents accidental release.

The curling iron is left upon the lock of hair over night or for a sufficient period to accomplish the curling and is then withdrawn by extending the iron, moving the 90 members to expanded position and drawing the same from the curl by an endwise movement.

The construction and mode of operation of the iron are exceedingly simple, as will 100 be readily evident. As many of these devices as are required may be worn with perfect comfort while sleeping. The irons may be produced at small cost. While I have found that an entirely satisfactory 105 curl can be produced with a cold iron, it should be distinctly understood that the iron may be applied hot if preferred.

I am aware that the form and arrangement of the parts may be varied without de- 110

parting from the spirit of my invention and I reserve the right to make all such as fairly fall within the scope of the following claims.

I claim as my invention:

- 5 1. A curling iron comprising a loop of resilient wire forming a handle, substantially hook-shaped hair gripping members pivotally connected to the ends of said loop and adapted to be turned to positions substantially within or without said loop, one of said members being provided with a longitudinal slot and the other member extending through said slot, said members being normally forced together by the spring action of the handle and being adapted to be moved apart by manual compression of said handle.
- 10 2. A hair curling device comprising a substantially U-shaped handle of spring metal, substantially hook-shaped hair gripping members pivotally connected to the ends of said loop and adapted to be turned from a position substantially within said handle to a position substantially without the same, one of said members being provided with a longitudinal slot and the other member ex-

tending through said slot, said members being normally forced together by the spring action of said handle and being adapted to be moved apart by the manual compression 30 of said handle.

3. A hair curling device comprising a substantially U-shaped handle of spring metal, substantially hook-shaped hair gripping members pivotally connected to the ends 35 of said handle and adapted to be turned from a position substantially within said handle to a position substantially without the same, one of said members being provided with a longitudinal slot and the other 40 member extending through said slot, said members being normally forced together by the spring action of said handle and being adapted to be moved apart by the manual compression of said handle, and means for 45 yieldingly retaining said members in their position within said handle comprising a projection on the handle and a notch formed in the end of one of said members to engage said projection.

WILLIAM D. SCHAEFER.
